UNITED STATES PATENT OFFICE.

HENRY DICKSON, OF PITTSBURG, PENNSYLVANIA.

APPARATUS FOR DRYING GREEN BRICK.

SPECIFICATION forming part of Letters Patent No. 290,823, dated December 18, 1883.

Application filed August 16, 1883. (No model.)

To all whom it may concern:

Be it known that I, HENRY DICKSON, of Tustin street, Pittsburg, Pennsylvania, have invented a new and useful Improvement in 5 Apparatus for Drying Green Brick, which improvement is fully set forth in the following specification, reference being had to the accompanying drawings.

Similar letters of reference indicate corresponding parts.

My invention relates to an improvement in apparatus for drying brick; and it consists in transmitting the heat of steam to the freshly-molded or "green" brick, in the manner and by the means which will hereinafter fully and at large appear.

Figure 1 is a top view or plan of the pipes I employ for transmitting the heat of steam to the brick to be dried. Fig. 2 is a transverse section of the drying-floor and the pipes embedded therein, said section of the pipes being at line *x x* of Fig. 1. Fig. 3 represents a transverse section of the same at line *c c* of Fig. 1.

In drying freshly-molded or green brick, I utilize the exhaust-steam of the engine, and when more heat is required than that produced by the exhaust-steam I combine with said exhaust-steam steam direct from the boiler or steam-generator. By the employment of steam and transmitting the heat thereof to the freshly-molded or green brick, uniformity or an even distribution of heat to all parts of the drying-floor is secured, which is a great desideratum in the operation of drying freshly-molded or green brick. The employment of steam for the purpose of transmitting its heat to the freshly-molded brick greatly diminishes the cost of drying the same, and experience has demonstrated that about one-half of the time usually required in the drying process is saved.

A B represent two pipes, which communicate with each other through the medium of pipes C, in the manner indicated in Fig. 1, the pipes A and B being of greater diameter than the pipes C. The pipes A, B, and C, coupled together, as shown in Fig. 1, are embedded in sand, and on this is placed a 50 coating of plastic clay, as shown at E, thereby

forming a drying-floor for the freshly-molded brick F.

To the pipe A is connected a pipe, *g*, which communicates with the exhaust-port of the steam-engine *h*, said engine being supplied with steam from the boiler or generator *j* through the medium of pipe *i*, which may be supplied with steam through the medium of a pipe, *m*. The pipes *i*, *m*, and *g* are furnished with valves. (Marked 1, 2, 3, 4, and 5.)

The outline of the building which covers the drying-floor is marked *k*.

The drying-floor being constructed as hereinbefore described, the operation of my process, combined with the apparatus, is as follows: The valve 1 of pipe *i* is open, and the valves 2 and 5 of pipe *g* are opened, the steam-valve 1 allows the steam to flow through pipe *i* into the cylinder of the engine *h*, and the opening of the valves 2 and 5 allows the exhaust-steam to flow through pipe *g* into the pipe A, from which it flows through pipes C into pipe B, thereby circulating the exhaust-steam throughout the whole series. The product of condensation may be carried off through pipe *b*, which is furnished with a valve, 6. When the exhaust-steam is insufficient, the valve 3 of pipe *m* may be opened slightly for combining with the exhaust-steam steam direct from the boiler by means of pipe *i*. In case the steam-engine is not in use, the steam direct from the boiler may be used. When it is not desirable to allow either the exhaust-steam or the steam direct from the boiler, the valves 3 and 5 are closed and valve 4 is opened, which will allow the steam exhausted from the engine to pass off through the pipe *n*.

Having thus described my invention, what I claim is—

1. The combination of the large steam-pipes A and B with the smaller transverse connecting steam-pipes C, and a system of supply pipes and valves whereby either exhaust-steam alone or exhaust-steam and steam drawn directly from the boiler may be supplied at will to said system of pipes A B C, the latter being arranged in the form of a frame under the floor of a kiln, for the purposes set forth.

2. A series of pipes communicating with 100

the exhaust-port of a steam-engine, and also directly with the boiler, in combination with valves for shutting off or opening communication with either or both of these sources of steam-supply, and a system of drying-pipes arranged under the floor of a kiln and receiving steam from the first-mentioned series.

In testimony that I claim the foregoing as my invention I hereto set my hand in presence of two witnesses.

HENRY DICKSON.
